US00D600949S

(12) **United States Design Patent**
Overthun et al.

(10) **Patent No.:** US D600,949 S
(45) **Date of Patent:** ** Sep. 29, 2009

(54) **SEATING UNIT**

(75) Inventors: **Thomas Overthun**, San Francisco, CA (US); **Lukas Scherrer**, San Francisco, CA (US); **James Ludwig**, East Grand Rapids, MI (US); **Bruce Smith**, Grand Rapids, MI (US)

(73) Assignee: **Steelcase Inc.**, Grand Rapids, MI (US)

(**) Term: **14 Years**

(21) Appl. No.: **29/318,690**

(22) Filed: **May 26, 2008**

(51) **LOC (9) Cl. 06-01**

(52) **U.S. Cl. D6/500; D6/366**

(58) **Field of Classification Search** D6/334-335, D6/364, 365, 366, 367, 369, 370, 374, 375, D6/379, 380, 498, 500-502; 297/411.4, 297/411.41, 445.1, 446.1, 452.12, 452.14, 297/452.15, 452.19, 452.29, 452.32

See application file for complete search history.

(57) **CLAIM**

We claim the ornamental design for a seating unit, as shown and described.

DESCRIPTION

FIG. 1 is a front perspective view of a seating unit according to the new design;

FIG. 2 is a rear perspective view of a seating unit shown in FIG. 1;

FIG. 3 is a front view of the seating unit shown in FIG. 1;

FIG. 4 is a right side view of the seating unit shown in FIG. 1, the opposed left side view being a mirror image thereof;

FIG. 5 is a rear view of the seating unit shown in FIG. 1; and,

FIG. 6 is a top view of the seating unit shown in FIG. 1.

In the drawings, features in broken lines form no part of the claimed design.

1 Claim, 6 Drawing Sheets
